UNITED STATES PATENT OFFICE

WALTER J. GRAHAM, OF MARIETTA, OHIO

DESIGN FOR A GLASS DISH OR SIMILAR ARTICLE

Application filed December 7, 1929. Serial No. 33,692. Term of patent 7 years.

To all whom it may concern:

Be it known that I, WALTER J. GRAHAM, a citizen of the United States, residing in Marietta, in the county of Washington and State of Ohio, have invented a new, original, and ornamental Design for Glass Dish or Similar Article, of which the following is a specification, reference being had to the accompanying drawing, forming a part thereof, in which the figure is a top plan view of a glass dish showing my new design.

It should be understood that the dotted line portions illustrated in the drawing are filled in the same as the portions shown in full line when actually reducing the design to practice.

I claim:

The ornamental design for a glass dish or similar article, as shown and described.

WALTER J. GRAHAM.
